United States Patent Office

Des. 223,949

Patented June 20, 1972

223,949

NOODLE PRESS

Gertrude Eipper, 1706 N. Arlington St.,
Milwaukee, Wis. 53202

Filed Nov. 5, 1970, Ser. No. 25,836

Term of patent 14 years

Int. Cl. D7—04

U.S. Cl. D44—29

FIG. 1 is a top plan view of a noodle press showing my new design;

FIG. 2 is a bottom plan view;

FIG. 3 is a rear elevational view;

FIG. 4 is a left end elevational view;

FIG. 5 is a right end elevational view; and

FIG. 6 is a top perspective view.

I claim:

The ornamental design for a noodle press, as shown.
